APPARATUS FOR CENTRIFUGAL PULVERIZING AND SEPARATING

John H. Macartney, San Francisco, Calif.

Application January 18, 1946, Serial No. 642,035

7 Claims. (Cl. 241—275)

1

This invention relates to an apparatus for grinding or pulverizing, and is particularly for the comminution and reduction of loose and broken lumpy material, such as ores, coal, cement, rock, clay and the like, to a required fineness of mesh. This application is a continuation in part of application Serial No. 554,186, filed September 15, 1944, now abandoned.

The features of the present invention include the grinding of the material by means of particles of the material thrown off by centrifugal force into contact with other particles of the material so that the grinding is effected by bombarding certain particles of the material by freshly introduced particles; the grinding is accomplished in a grinding chamber formed between oppositely rotating bodies in each of which a portion of the material is so restrained as to form grinding surfaces or linings on the inner peripheries of the respective rotating bodies; particles of said material being drawn through said chamber and into the path of the centrifugally thrown particles by suction which is partly created by the rotation of said linings and bodies; the said linings and bodies being preferably rotated in opposite directions, and preferably these rotating bodies being positioned one in the other and being rotated oppositely to one another.

An object of the invention is to utilize the centrifugal force for imparting grinding velocity to particles of the material directed into a grinding chamber and to utilize the same force for moving particles in the path of the centrifugally thrown particles and to move the material ground to suitable fineness out from said chamber.

Other objects of the invention together with the foregoing will be set forth in the following description of the preferred embodiment of means for practicing the same, which is illustrated in the drawings accompanying and forming part of the specification. It is to be understood that I do not limit myself to the embodiment disclosed in said description and the drawings as I may adopt variations of my preferred forms within the scope of my invention.

A preferred embodiment of the invention is clearly illustrated in the accompanying drawings, wherein:

Fig. 1 is a cross-sectional view of an embodiment of my invention, the section being taken on lines 1—1—1—1 of Fig. 3;

Fig. 2 is a sectional plan view of the apparatus, the section being taken on the line 2—2 of Fig. 1;

2

Fig. 3 is a sectional plan view of the apparatus, the section being taken substantially on lines 3—3 of Fig. 1;

Fig. 4 is a sectional, fragmental detail view of one of the screened outlets from the outer cone of the apparatus;

Fig. 5 is a sectional, fragmental view showing said outlet covered;

Fig. 6 is a sectional view of a modified form of my invention;

Fig. 7 is a fragmental, sectional top plan view of the outer cone of the modified form with side outlets, and

Fig. 8 is a plan, diagrammatic view indicating substantially the paths of the opposed streams in the device.

In carrying out my method of grinding and pulverizing material such as ore, clay or the like, the material is fed centrally into a rotating inverted cone closed at its apex and open at its base so that the centrifugal force carries the particles of material upwardly along the inner periphery of said cone. The material is restrained partially so as to form into a lining layer on the inner periphery of the cone. Particles of the material from the surface of this layer are impelled by the centrifugal force upwardly and radially outwardly from the base of the cone across and into a grinding chamber formed between the aforementioned cone and a spaced exterior cone rotated concentrically with the first cone. The material in this outside cone is rotated in opposite direction to the rotation of the material in the inner cone and it is restrained partially so as to form a layer or lining on the inner periphery of this outer cone. The particles of material in the inner layer are rotated at a much higher speed than the particles of material in the outside layer and in the chamber. The centrifugal force of the outer layer urges the particles in said chamber upwardly and toward the portion of the chamber which is adjacent to the area into which the particles from the first cone are ejected by the centrifugal force. In effect, the particles in the outer layer are carried in a continuous stream into the path of the stream of particles centrifugally fed from the inner layer and are practically bombarded by the particles flying off from the base of the inner cone.

A feeding effect in an upward direction is created by the rotation of the inner cone to facilitate the upward movement of the particles from the outer layer and into suitable position for the bombarding action of the outwardly flying particles. The whirling particles which move

at a high speed work against the respective layers of particles in the inner and outer cone so that the particles of material form also the wearing surfaces during the grinding. Thus, in my method, the particles of material successively operate for grinding the previously introduced particles of material by a bombarding action and also form protective linings which provide the wear surfaces during the grinding. The feeding into the inner lining or cone is so performed that the material is introduced near the apex of the inner cone. The upward draft produced by the rotation of the opposite linings and cones moves the particles upwardly in the grinding chamber and allows the heavier particles to drop back and be again advanced for further bombarding action and grinding. The dropping heavier particles contact the lining in the outer cone and are held up and urged upward again by the centrifugal force exerted on them by the rotating outer cone. Thus the material in the outer cone is prevented from falling through the open bottom of said outer cone. The lighter particles of finer mesh are also carried upwardly by said draft and out through an outlet passage, which is suitably restrained to pass only particles of a desired fineness. The ground material is then collected and removed at a point above said rotating mechanism.

In the preferred form of my invention, as illustrated in the drawings, I use an inverted hollow cone 6, the apex 7 of which is closed and the base 8 of which is open. The apex 7 of the cone 6 is mounted on a shaft 9 which latter in turn is supported in suitable bearings 11 in frame members 12 and on a base 13. On the cone base 8 is formed a restraining rim 14 projecting inwardly of the cone 6 so as to restrain a portion of the material in the rotating cone in such a way that a layer of material is formed all around the inside wall of the hollow cone 6 producing a protective lining in the cone. The rim 14 has converging sides cross-sectionally and the outer inclined sides of the rim 14 assists somewhat in directing particles of the material to fly substantially radially outwardly from the cone base 8. The outer face 15 of the rim 14 is comparatively flat and then tapers outwardly of the cone and downwardly so as to give corresponding direction to the particles flying off the cone base 8.

Around the outer periphery of the cone 6 is formed a gritting or grinding chamber 17. The outer wall of this chamber 17 is formed by an inverted frusto-conical shell 18 spaced from the outer surface of the inside cone 6. A portion of the wall of this outer shell 18 is substantially parallel and concentric with the outer surface of the inner cone 6, but this parallel portion terminates at a level 19 which is below the level of the base rim 14 of the inner cone 6. The wider mouth or base 21 of the outer shell 18 is inclined at a steeper angle than the conical portion of the shell 18 and extends above the level of the base rim 14 of the inner cone 6. On the inner periphery of the shell 18 is a restraining flange 22 which extends at an angle upwardly and toward the inner cone 6. The function of this flange 22 is to collect certain of the material adjacent the wall of the shell 18 into lining which lining then completely covers the inner surface of said shell 18. In the top of the outer shell 18 is a cover plate 23 which extends outwardly beyond and outside the top edge of the shell 18 and forms a circular centering flange 24.

A vertical frame 26 extends from the base 13 upwardly and spaced from the outside of the shell 18. On the top of this frame 26 are rotatably mounted a plurality of idler rollers. The outer periphery of the centering flange 24 is in frictional contact with the peripheries of the idler rollers 28 so that as the shell 18 rotates it will cause the rotation of the idler rollers 28 which latter center and guide the shell 18.

The inner cone 6 is rotated in one direction and the outer conical shell 18 is rotated in the opposite direction by any suitable means. In the present illustration an electric motor or the like, not shown, is connected by suitable transmission, such as a belt transmission 32 to the shaft 9 which latter is shown, in the present illustration, fixed to the apex 7 of the cone 6 by means of a key 33.

In the present illustration the shell 18 has an annular base flange 34 on its outer periphery spaced from the lower end thereof and facing downwardly. A plurality of supporting rollers 35 are rotatably mounted on brackets 36 on a frame member 12 under said flange 34. The base flange 34 rides on the supporting rollers 35 when the shell 18 is rotated and supports the shell 18. Slightly above and outside the flange 34 is formed a ring gear 37 on the shell 18. A drive gear 38 is in mesh with the ring gear 37 for imparting rotation to the shell 18. The drive gear 38 is keyed on a drive shaft 39, which latter is journalled in bearing brackets 40 on the frame members 12, and is driven by any suitable power drive through a suitable transmission, such as the belt and pulley drive 41. The transmission heretofore described is arranged for rotating the shell 18 in a direction opposite to the direction of rotation of the cone 6. The relative rotative speeds are preferably such that the speed of rotation of the shell 18 is considerably lower than that of the inner cone 6. For instance, for certain purposes of grinding certain materials, the cone 6 is rotated at about 2000 revolutions per minute in one direction while the outside cone or shell 18 is rotated at about 500 revolutions per minute in the opposite direction.

Above the cover plate 23 is formed a collecting chamber 51 by a lid 52 which is supported on suitable brackets 53 extended from the top of the vertical frame 26. A hopper tube 54 is secured in the center of the lid 52 and is extended downwardly and through the cover plate 23 and into the cone 6 to a point near the apex 7 of said cone 6. Material is fed into this hopper tube 54 at a funnel top 56 in any suitable manner. From the lid 52 extends a delivery conduit 57 which is connected to a booster fan or blower indicated at 58 in Fig. 1.

On the outer surface of the cone 6 are provided a plurality of vanes 59 at a suitable angle to create a draft or blast upwardly through the gritting chamber 17 and toward the cover plate 23. The cover plate 23 has a plurality of outlet openings 61 therethrough, covered by screens 62 of suitable mesh so as to allow only particles of predetermined fineness to be discharged from the grinder.

Each outlet opening 61 is surrounded by flanges 63. It is to be noted that each opening 61 is defined by concentric arcuate sides and all the openings 61 lie at the same radial distance from the center of the cover plate 23. Inasmuch as the cover plate 23 rotates with the shell 18 in a counter-clockwise direction viewing Fig. 2, the arcuate side flanges

63 are inclined so as to present a higher edge 64 as the leading edge in the direction of rotation as shown particularly in Fig. 4. Each screen 62 is arranged to follow the incline of the arcuate flanges 63, so that the screens 62 also incline downwardly toward the trailing end oppositely to the direction of rotation of the cover plate 23. This inclined arrangement produces a lift or suction above each screen 62 and facilitates the drawing of the ground particles through said screens 62.

A set of outlets 66 is arranged near the center of the cover plate 23. These outlets 66 are adjustably controlled by a valve plate 67 which is rotatably held by set screws 68 which latter are slideable in arcuate slots 69 on said valve plate 67. The valve plate 67 has a pair of opposite openings 71. In the position shown in Figs. 1 and 2 of the drawings, the central outlets 66 are covered by the plate 67. When greater fineness is desired, the valve plate 67 is turned until the openings 71 are in a desired alignment above the outlets 66 for forming the desired opening. When the central outlets are used, the outer outlets 61 are covered by plates 72 as particularly shown in Fig. 5. This selective adjustment is accomplished after raising the cover or hood 52 sufficiently to gain access to the top of the cover plate 23.

At the bottom of the shell 18 are openings 73 covered and adjusted by a valve plate 74 similar in structure and operation to the valve plate 67 heretofore described. The bottom openings 73 are adjusted for the desired intake to maintain a balanced pressure condition for the air flow through the shell 18.

In the modified form of the invention, shown in Figs. 6 and 7 an apparatus is shown to carry out my invention in connection with wet material. This apparatus and the principle of operation is substantially the same as heretofore described in the first form, with certain differences. The cover plate 23' is entirely closed, and outlets 75 are provided along the periphery of the shell 18'. In each outlet 75 is a screen 76 of suitable mesh. The shape of the shell 18' is different in that the lower portion is sloped at lesser incline to the horizontal. The outlets 75 are below the level of the upper edge 16 of the inner cone 6. The wet material is agitated and is moved continuously upward in the outer shell 18' by the centrifugal force and it is subjected to bombardment by the outwardly thrown particles from the top of the inner cone 6 repeatedly, and is also ground by continuous contact in its relative movement upon each other. The particles ground to the desired size are permitted to escape through centrifugal force through the outlet screens 76 and are collected by any suitable means not shown.

In Fig. 8 is shown diagrammatically the general path and direction of the movement of the particles from the inner cone and in the outer shell. The outer shell rotates in counter-clockwise direction and the inner cone rotates in clockwise direction viewing Fig. 8. It was observed that the particles from the inner shell follow substantially the paths indicated by the broken lines and arrows 77. The paths of the particles ejected by centrifugal force from the inner cone are substantially radial and curve toward the direction of rotation. The particles in the outer shell 18 move substantially on curved paths indicated by broken line arrows 78 in Fig. 8. These paths 78 are along the inner conical surface of the lining layer or of the shell 18, and move upwardly and

also toward the direction of rotation of the outer shell 18. The horizontal streams of particles ejected with high speed from the inner cone 6 collide with and bombard the particles which move upwardly and substantially outwardly on the paths 78 in the outer shell 18. The rotational direction and force on these particles is at an intersecting angle with respect to the horizontally thrown particles. The general movement of the particles in the outer shell 18 is upward although not exactly on a vertical path. The particles in the outer shell collide also with one another and during the movement along the outer shell the frictional contacts therein effect further attrition or comminution of said particles. When these particles in the shell 18 reach into the path of the substantially horizontal stream of particles ejected from the inner cone 6, they are effectively bombarded with still greater force. By the combined frictional forces and collisions between the particles a comparatively speedy and uniform pulverizing or comminution is accomplished. The upward movement of these particles is maintained in a comparatively balanced draft, namely, the blower or fan 58 produces a suction to draw the particles out through the respective discharge outlets 61 or 66. The vanes 59 on the outer periphery of the cone 6 create a draft upward to feed the air in the direction of said suction. The bottom intakes 73 of the outer shell 18 are adjusted to admit the necessary air for a balanced upward air current which aids in the discharging of the finely ground particles through said outlets, but permits the heavier particles to fall back into the outer shell 18 and work in the aforesaid described paths into repeated collisions with other particles until reduced to desired fineness.

In operation the material is fed centrally through the hopper tube 54 and is introduced into the rotating inner cone 6 near the bottom apex 7 thereof. The method and apparatus herein described performs the attrition of particles of the material to be ground by collision between streams of such particles travelling on intersecting paths at high velocity imparted by centrifugal force. For instance a cone of about 29½" diameter, may rotate at a speed of 1750 revolutions per minute and it will discharge the particles in a substantially horizontal plane at the base of the cone at about 14,000 feet per minute into and across the grinding chamber 17. The centrifugal force urges the particles of material upwardly in the cone and radially outwardly at the base rim 14 of the cone 6. Certain of the particles closer to the inner surface of the cone 6 are partly obstructed and restrained in their upward movement by the rim flange 14 and accumulate into a circular lining or liner on the inner surface of the cone 6 so that the particles moving at high speed impinge upon the liner of the material instead of upon the surface of the cone 6.

The outer cone or shell 18 is rotated at a lower velocity than the inside cone 6. For instance, with an outer cone of 42" diameter at 200 revolutions per minute, it would move particles collected in said shell 18 at a velocity of about 2200 feet per minute generally upwardly and in the path of the stream of particles discharged at a higher velocity from the inner cone 6. The two streams of particles so driven collide in the grinding chamber 17 and this collision between the two streams of particles breaks up the particles into smaller pieces and performs the grind-

ing operation. The lower retaining flange 22 on the outer shell 18 in combination with the steeper base portion of the conical outer shell 18 will collect a certain portion of the material as a liner around the inner surface of the shell 18 so that the particles in the grinding chamber 17 will not impinge upon the material of the shell 18 but this liner so formed will take up the wear and also causes further attrition of the particles of material to be ground. During this opposite rotation of the inner cone 6 and the outer shell 18, the vanes 59 on the outer surface of the inner cone 6 move within the grinding chamber 17, create a blast of air which may reach a velocity of about 12,000 feet per minute in connection with structures of the size heretofore mentioned. The ground particles will fall back into the chamber 17 and against the liner layer on the sides of the shell 18 until ground to such a fineness that they can pass through the screen 62 of the outlets 61 and carried away from the collection chamber 51 through the discharge conduit 57. There is a rotary clearance between the lid 52 and the flange 24 of the cover 23, and to prevent lateral escape of ground product, I provide an annular shield 19 extending upwardly from the cover 23 along the inside periphery of the lid 52. This upward blast or draft created by the vanes 59 also cooperates with the centrifugal force in the device for moving the particles upwardly and preventing them from falling through and out the open bottom of the frusto-conical shell 18. It is to be understood that the dimensions and speeds of rotation above enumerated are merely for the purpose of illustration as they were found operable in connection with certain types of material to be ground, but applicant does not wish to be bound or limited to any dimensions or rotating speeds described herein for the purpose of illustration.

The principle of operation of grinding material by driving two streams of particles of such material at high speed so as to collide with a bombarding effect utilizes the centrifugal force of the oppositely rotating cones and the layers of linings of the same material on the wearing surfaces of said cones and makes use both of the centrifugal force created and also of the wearing action on the lining for grinding the particles of material to a desired fineness. It accomplishes the grinding with greater efficiency and in comparatively greater volumes; it reduces the wear of the revolving parts participating in the grinding operation, the wear being taken up by the liners created by the material itself; it also reduces the comparative power per unit required for a desired output; it operates continuously and uninterrupted without the danger of clogging or breakdown from the point of the introduction of the material to be ground near the apex of the inner cone 6, then upwardly and outwardly, forming the lining in the inner cone and flying off at a high speed into the grinding chamber 17 through the upwardly travelling stream over and from the lining layer of the outer cone or shell 18. The two cones operate preferably with a vertical axis, as shown, concentrically in opposite directions at suitable relative speeds, not requiring any adjustment or any regulation during the continuous operation of the grinder.

I claim:

1. In a machine of the character described, a hollow inverted cone, and an outer shell around said cone having upwardly diverging walls spaced from said inner cone, means to rotatably support

said cone and shell on a substantially vertical common axis of rotation, means to rotate said cone and said shell in opposite directions to one another, and to rotate said inner cone at higher speed of rotation than said outer shell, the base of the inner cone being adapted to throw particles of material substantially laterally outwardly from the inner cone against the outer shell, the angle of incline of the walls of said outer shell guiding the particles dropped into said outer shell upwardly and across the path of the particles thrown off from the base of the inner cone.

2. In a machine of the character described, a pair of hollow elements having upwardly diverging walls, one element being disposed within substantially parallel with and spaced from the other, means to rotate said elements in opposite directions to one another around a common vertical axis and to rotate the inner element at a higher speed than the outer element, means to feed material to be comminuted into the inner element, said inner element being adapted to eject by centrifugal force particles of said material toward the outer element and into forceful impact with other particles of material urged upwardly in the outer element by centrifugal force of said rotation, and retaining means in each of said elements to retain part of the material in the respective elements in the form of lining layers on the inner surfaces of the respective elements.

3. In a machine of the character described, a frame, a hollow inverted cone rotatably supported in the frame, an outer shell with upwardly diverging walls spaced outside of the first cone, a supporting flange extended outwardly from the top of the outer shell, rotary aligning means to rotatably support said flange and said outer shell on said frame, means to rotate said cone and said shell in opposite directions to one another about a common vertical axis and rotate the inner cone at a higher speed than said outer shell, retaining rims on the cone and on the shell for retaining part of the material in the form of conical linings therein, the top edge of the inner cone directing particles of material thrown off by centrifugal force laterally outwardly into impact with other particles moved by centrifugal force upwardly in said outer shell, and impeller blades formed on the inner cone and extended into the space between said cone and shell for creating an upward draft between said cones.

4. In an apparatus of the character described, a frame, a hollow inverted cone rotatably supported on the frame, a hollow inverted substantially frusto-conical shell rotatably supported on the frame, rotating outside of and being concentric with said first cone, said cone and said shell diverging upwardly, means to rotate said cones in opposite directions to one another around a substantially vertical common axis, the upper edge of said inner cone being adapted to throw material therefrom laterally against said outer shell, means to feed the material to be treated into the inner cone adjacent to the apex thereof, and outlet means for discharging material comminuted to desired fineness from said outer shell.

5. In an apparatus of the character described, a frame, a hollow inverted cone rotatably supported on the frame, another hollow inverted cone rotatably supported on the frame, rotating within and being concentric with said first cone, said cones diverging upwardly, means to rotate said cones in opposite directions to one another, means to feed the material to be treated into the

inner cone adjacent to the apex thereof, and outlet means for discharging material comminuted to desired fineness from said outer cone, said outlet means including a cover plate on said outer cone spaced above the base of said inner cone, a lid above said cover plate forming a discharge chamber, and outlet ports on said plate discharging into said chamber, the said outlets being arranged in a pair of concentric series at different radial distances from the center of rotation of 10 said cones, and means to close the respective series of outlets and at will.

6. In an apparatus of the character described, a frame, a hollow inverted cone rotatably supported on the frame, another hollow inverted 15 cone rotatably supported on the frame, rotating within and being concentric with said first cone, said cones diverging upwardly, means to rotate said cones in opposite directions to one another, means to feed the material to be treated into the 20 inner cone adjacent to the apex thereof, and outlet means for discharging material comminuted to desired fineness from said outer cone, and a series of outlets on the periphery of the outer cone below the level of the base of the inner cone. 25

7. In an apparatus of the character described, a frame, a hollow inverted cone rotatably supported on the frame, another hollow inverted cone rotatably supported on the frame, rotating within and being concentric with said first cone, said 30 cones diverging upwardly, means to rotate said cones in opposite directions to one another, means to feed the material to be treated into the inner cone adjacent to the apex thereof, and outlet means for discharging material comminuted to 35 desired fineness from said outer cone, said outlet means including a cover plate on said outer cone spaced above the base of said inner cone, a lid above said cover plate forming a discharge chamber, and outlet ports on said plate discharging 40

5 into said chamber, flanges surrounding said outlets and extended upwardly into said chamber, said flanges being provided with higher leading edge in the direction of rotation, and a screen in each of said outlets arranged at an incline upwardly toward the direction of rotation of said cover plate and of said outer cone for creating a lift above said screens in said outlets.
